UNITED STATES PATENT OFFICE

100,000

DESIGN FOR AN ARTICULATED RAIL CAR OR SIMILAR ARTICLE

Everett Eugene Adams, Martin P. Blomberg, and William H. Mussey, Chicago, Ill., and William B. Stout, Detroit, Mich., assignors to Pullman-Standard Car Manufacturing Company, Chicago, Ill., a corporation of Delaware

Application May 9, 1935, Serial No. 56,754

Term of patent 14 years

To all whom it may concern:

Be it known that we, Everett Eugene Adams, Martin P. Blomberg, William H. Mussey, and William B. Stout, citizens of the United States of America, Everett Eugene Adams, Martin P. Blomberg, and William H. Mussey being residents of Chicago, county of Cook, and State of Illinois, and William B. Stout being a resident of Detroit, county of Wayne, and State of Michigan, have invented a new, original, and ornamental Design for an Articulated Rail Car or Similar Article, of which the following is a specification, reference being had to the accompanying drawing, forming a part thereof, wherein

Fig. 1 is a plan view showing our new design for an articulated rail car or similar article;

Fig. 2 is a side, elevational view of the same;
Fig. 3 is a perspective view, the point of view being adjacent to the front end of the car;
Fig. 4 is a front, elevational view;
Fig. 5 is a rear, elevational view; and
Fig. 6 is a perspective view, the point of view being adjacent to the rear end of the car.

Figs. 1 and 2 are drawn to a slightly smaller scale than the remaining figures.

We claim:—

The ornamental design for an articulated rail car or similar article as shown.

EVERETT EUGENE ADAMS.
MARTIN P. BLOMBERG.
WILLIAM H. MUSSEY.
WILLIAM B. STOUT.
